DESIGN FOR AN ELECTRIC SWITCH

Rudolf Popp, Valparaiso, Ind., assignor to McGill Manufacturing Company, Valparaiso, Ind., a corporation of Indiana

Application February 20, 1943, Serial No. 109,593

Term of patent 14 years

To all whom it may concern:

Be it known that I, Rudolf Popp, a citizen of the United States, residing at Valparaiso, in the county of Porter and State of Indiana, have invented a new, original, and ornamental Design for an Electric Switch, of which the following is a specification, reference being had to the accompanying drawing, forming part thereof, in which:

Fig. 1 is a perspective view from the top and one side of an electric switch showing my new design;

Fig. 2 is a bottom perspective view;
Fig. 3 is a side elevational view;
Fig. 4 is an end elevational view; and
Fig. 5 is a top plan view.

The dominant features of my new design are shown in solid lines in the drawing.

I claim:

The ornamental design for an electric switch, substantially as shown and described.

RUDOLF POPP.
